United States Patent Office

Des. 215,671

Patented Oct. 21, 1969

215,671

DISPENSER FOR SHEET MATERIAL

Harry F. Knight, Jr., Terrace Park, and Donald E. Coyle, Cincinnati, Ohio, assignors to Clopay Corporation, Cincinnati, Ohio, a corporation of Maryland

Filed Oct. 30, 1968, Ser. No. 14,237

Term of patent 14 years

Int. Cl. D9—04

U.S. Cl. D52—2

The dominant features of our design reside in the portions shown in full lines.

We claim:

The ornamental design for a dispenser for sheet material, substantially as shown and described.
